US00D804435S

(12) **United States Design Patent** (10) Patent No.: **US D804,435 S**
(45) Date of Patent: ** Dec. 5, 2017

(54) **FLAP IN AN ADHESIVE TAPE FOR SEMICONDUCTOR MANUFACTURING**

(71) Applicant: **HITACHI CHEMICAL COMPANY, LTD.**, Tokyo (JP)

(72) Inventors: **Kouhei Taniguchi**, Ichihara (JP); **Takayuki Matsuzaki**, Ichihara (JP); **Shinya Katou**, Ichihara (JP); **Kouji Komorida**, Ichihara (JP); **Michio Mashino**, Ichihara (JP); **Tatsuya Sakuta**, Ichihara (JP); **Rie Katou**, Ichihara (JP)

(73) Assignee: **Hitachi Chemical Company, Ltd.**, Tokyo (JP)

(**) Term: **14 Years**

(21) Appl. No.: **29/491,391**

(22) Filed: **May 20, 2014**

(57) **CLAIM**

The ornamental design for a flap in an adhesive tape for semiconductor manufacturing, as shown and described.

DESCRIPTION

FIG. 1 is a top plan view of a flap in an adhesive tape for semiconductor manufacturing incorporating our new design; FIG. 2 is a bottom plan view of the flap of FIG. 1; FIG. 3 is a cross-sectional view taken at line 3-3 in FIG. 1; FIG. 4 is an enlarged view of portion 4-4, 4-4 in FIG. 1; and, FIG. 5 is a perspective view of the flap in use. The broken lines are included for the purpose of illustrating environmental structure and form no part of the claimed design.
